Primary Examiner — Robin V Webster*(74) Attorney, Agent, or Firm* — Michael Best & Friedrich LLP(57) **CLAIM**

I claim the ornamental design for a shower head, as shown and described.

DESCRIPTION

FIG. 1 is a front view of a shower head; and, FIG. 2 is a perspective view of the shower head shown in FIG. 1.

The broken lines having equal length segments in the figures represent portions of the shower head that form no part of the claimed design. The broken lines having unequal length segments illustrate the boundaries between claimed and unclaimed portions of the design.
